UNITED STATES PATENT OFFICE.

FRED ARNOLD, OF LAKWOOD, OHIO.

DESIGN FOR A SEWING-MACHINE HEAD.

Application filed January 1, 1926. Serial No. 15,920. Term of patent 7 years.

To all whom it may concern:

Be it known that I, FRED ARNOLD, a citizen of the United States, residing at Lakewood, in the county of Cuyahoga and State of Ohio, have invented a new, original, and ornamental Design for a Sewing-Machine Head, of which the following is a specification, reference being had to the accompanying drawing, forming a part thereof.

Fig. 1 of the drawing is a side view of the

head; Fig. 2 is a side view, but looking at the opposite side thereof; Fig. 3 is a plan view of the bed of the head with the upright portion of the arm in section; and Fig. 4 is an end view looking toward the outer end of the arm.

I claim:

The ornamental design for a sewing machine head substantially as shown.

FRED ARNOLD.
